US00D704685S

(12) **United States Design Patent**
Yeh et al.

(10) **Patent No.:** **US D704,685 S**
(45) **Date of Patent:** **** May 13, 2014**

(54) **HOUSING**

(75) Inventors: **Guo-Liang Yeh**, New Taipei (TW);
Po-Ching Huang, New Taipei (TW);
Tzu-Cheng Yu, Santa Clara, CA (US)

(73) Assignee: **Chi Mei Communication Systems, Inc.**, New Taipei (TW)

(**) Term: **14 Years**

(21) Appl. No.: **29/419,224**

(22) Filed: **Apr. 26, 2012**

(30) **Foreign Application Priority Data**

Feb. 15, 2012 (CN) 2012 3 0290044

(51) **LOC (10) Cl.** **14-03**

(52) **U.S. Cl.**

USPC **D14/248**

(58) **Field of Classification Search**

USPC ..... D14/138 AA, 138 AB, 138 AC, 138 AD,
D14/138 G, 138 R, 140, 168, 169, 172, 203,
